UNITED STATES PATENT OFFICE.

THOMAS F. GAYNOR, OF NEW YORK, N. Y.

SELF-FILLING FOUNTAIN-PEN.

977,424.

Specification of Letters Patent. Patented Nov. 29, 1910.

Application filed April 25, 1910. Serial No. 557,894.

To all whom it may concern:

Be it known that I, THOMAS F. GAYNOR, a citizen of the United States, and a resident of Brooklyn, New York city, in the county of Kings and State of New York, have invented certain new and useful Improvements in Self-Filling Fountain-Pens, of which the following is a specification.

This invention relates to self-filling fountain pens, of the class having compressible elastic ink reservoirs within their handles which are operated by means of presser bars resting upon the reservoirs having finger pieces extending therefrom through slots in the handles which when pressed downwardly cause the reservoirs to supply the ink to the pen points as desired, or else by making a partial vacuum in the reservoirs after the pressure thereon has been released—to cause a new supply of ink to enter the reservoirs when the latter are in need of refilling—and the pen points dipped into a body of ink for the purpose, in a manner now generally well known to persons using devices of this nature.

The invention consists in providing the finger piece with a guard or shield alongside of the finger piece and in movable relation therewith, so that the degree of pressure upon the finger piece can be regulated and the flow or supply of ink to the pen point controlled at will and incidentally the guard serving to protect the finger piece against accidental depression and consequent ejection of the ink from the reservoir when it might be undesirable.

The object of the invention, is to provide a pen of this class with a quick-acting means of controlling and regulating the supply and flow of ink into and from the reservoir and by quick and simple manipulations of the device and at the same time properly protecting the finger piece against accidental depression and ink discharge resulting therefrom. Self-filling pens of this compressible reservoir and presser bar-finger piece construction are now the quickest acting and simplest of manipulation, of all styles of self-filling pens, and are very popular, but all designs so far as is known are provided with and require means for locking the finger piece and presser bar against accidental ink discharge from the reservoir, and they are not provided with means for partial depression of the finger piece and presser bar

at all, so that moving the locking mechanisms and manipulating the finger pieces takes considerable time and careful manipulation relatively, and the flow of the ink from the reservoir to the pen point cannot be controlled and regulated as well as it should be, and it is to obviate these objections and meet the requirements of a simpler, quicker acting and better device, that this invention is produced.

The nature and objects of the invention will be better understood from the following specification taken in connection with the accompanying drawings forming a part thereof, and in which similar letters refer to similar parts throughout the several views.

In the drawings:—Figure 1, represents a side elevation of a pen partly in section provided with this improvement. Fig. 2, is a transverse section of Fig. 1, through the finger piece and guard and the central portions thereof. Fig. 3, is a plan or top view of Fig. 1, looking downwardly upon the finger piece and guard and its moving sleeve connection. Fig. 4, is a transverse section of Fig. 3, through the centers of the finger piece and guard, only that the guard is shown as being moved away to the limit from the finger piece. Fig. 5, is a side elevation of finger piece the top of which has a curvature and length nearly equal to that of the guard and the shape of the sleeve slightly different from that shown in Fig. 3, as will be explained more fully hereafter. Fig. 6, is a transverse section through the centers of the finger piece and guard seen in Fig. 5, and showing that the slit in the sleeve extends to the end thereof. Fig. 7, is a top view of a finger piece and guard having a narrow sleeve connection and the barrel of the pen having limiting grooves therein that limit the rotation of the guard away from the finger piece. Fig. 8 is a transverse section of Fig. 7, through the center thereof and showing how the thumb or finger of a user of the device can cause a partial depression of the finger piece and a consequent supply of ink to the pen point whenever wanted without moving the guard away from the finger piece. Fig. 9, is a side view of a finger piece and guard similar to those shown in Figs. 5 and 6, only that the guard is provided with a flange over the finger piece and leaving a slot between the flange and top of the finger piece into which the finger or

thumb nail can be inserted and the finger piece thereby depressed without uncovering the finger piece. Fig. 10, is a transverse section of Fig. 9, through the center thereof. 5 Fig. 11, is a side elevation of a finger piece and guard slitted longitudinally so that a part of the guard is each side of the finger piece, and in which case the guard with its controlling sleeve is arranged to be moved 10 lengthwise over the barrel instead of rotatively as in the other designs. Fig. 12, is a transverse section of Fig. 11, on the line $a-b$, therein, and showing the slitted construction of the guard and finger piece centrally located therein. Fig. 13, is a top view 15 of Figs. 11 and 12, and showing the finger piece and guard in the closed position, Fig. 11 showing these members in the open position instead. Fig. 14, is an enlarged view 20 of Fig. 4, and shows a depression in the surface of the barrel into which the guard enters and becomes secured against accidental rotation when alongside of the finger piece. Fig. 15, is a perspective view of the design 25 seen in Figs. 1, 2, 3 and 4, with the guard drawn away from the finger piece and the latter being depressed by the thumb of a person about to compress the ink reservoir as in the case of refilling the latter, or the like. 30 Figs. 16 and 17, are perspective views of the guard in one and two sections respectively, with notches therein, and extending over the top of the finger piece.

In the drawings:—A represents a pen 35 point held within the shell B, by the plug C, having the usual ink duct C', and the shell B, being screwed or frictionally fitted to the handle or barrel D, in the manner of general pen holder construction for pens of this 40 class. An ink reservoir E, is secured to the inner end C², of the plug C, of rubber or other compressible material and lies loosely within the cavity D', of the barrel D, and against its outer surface rests the presser 45 bar F, having the finger piece G, secured thereto and extending outwardly through a corresponding slit in the wall of the barrel so that the presser bar can be made to compress the ink reservoir and to discharge the 50 ink therefrom to the pen point by the depression of the finger piece from the outside of the barrel, and all of which construction is now well known and in general use.

Unless the finger piece is locked in position 55 or other provision made against such a contingency, it is sometimes liable to become depressed accidentally and the ink forced out of the reservoir when not required, and this invention provides for such an emergency by arranging alongside of the finger piece the guard H, of substantially the same shape and dimensions as those of the finger piece and as high or higher from the outer surface of the barrel as the finger piece projects therefrom. In the first ten figures of

the drawings, the guard is shown as being higher than the finger piece is from the barrel, while in the figures numbered 11 and 13, it is shown as being partly higher and partly lower than the top of the finger piece 70 on account of the transverse notch I, in the guard which allows for a partial depression of the finger piece without necessitating the moving away from the finger piece of the guard, as will be more fully explained hereinafter. Now by having the top of the guard as high from the barrel as the top of the finger piece is, or higher, the finger piece cannot be depressed by anything that would ordinarily come against these members accidentally, as the impinging object would make contact with the top of the guard which is non-depressive and it would take and resist the downward pressure of the said object and thus guard the finger 80 piece against such pressure. Any such accidental depressing object would most likely be broad enough to touch the top of the guard as soon or before touching the top of the finger piece and thus the latter would be 85 guarded against depression while the guard is alongside of the finger piece. Nothing but a very thin or sharp object could be made to depress the finger piece and clear the top of the guard and the adjacent surface of the barrel, as can be seen in Fig. 8, where the thumb or finger of a person is shown as trying to depress the finger piece but it can do so only very slightly on account of its resting against the top of the 100 guard and the surface of the barrel mainly and only slightly depressing the finger piece, but which slight depression of the finger piece is in this case one of the purposes of the invention, that is, to cause a 105 slight depression of the presser bar and discharge of ink from the reservoir to give a small regulated supply of ink to the pen point whenever needed, as is frequently the case with pens of this construction. Even 110 this remote contingency of compression of the finger piece by the pressure thereon of a sharp object, can be provided against by having a lateral flange project from the top of the guard as seen in Figs. 9 and 10, where 115 the guard H', has the flange H², which leaves a narrow groove J, between the under surface H³, of the flange and the top G', of the finger piece G², and into which the finger or thumb nail of a person can be inserted, and thus made to depress the finger piece as may be desired. It has been found in practice however that the said flange is hardly ever needed as an additional precaution 120 against accidental depression of the finger piece and that the construction shown in the other figures is sufficient to meet all the requirements of ordinary practice.

When the finger piece is to be entirely depressed however this can be done by mov- 130

ing the guard away from the finger piece sufficiently to allow this being done, and Fig. 4, shows substantially the extent that it is found necessary to separate the guard from the finger piece in such a case. Fig. 15 also shows the extent of separation of the finger piece and guard required and the finger piece being in the act of depression by the thumb of a person, while the whole device 10 is held in the hand during the operation.

To give the proper movement and control of the guard, the latter is shown as connected to or mounted upon a sleeve K, which has a tight tensional fit around the outside 15 of the barrel and in a corresponding groove in the latter and which is of the same width as the length of the sleeve and by means of which, the latter is prevented from moving endwise on the barrel while being allowed a 20 rotatable movement around it as indicated in Fig. 4, where the dotted lines indicate the angle of rotation of the sleeve and guard.

In Figs. 11, 12 and 13, however, the guard is shown as being of two sections H⁴, H⁵, 25 secured to the sleeve K', in such a manner as to leave a slit L, between them in which the finger piece G³, slidably fits and projects. The sleeve K', is shown in Fig. 11, as being drawn away lengthwise upon the barrel D², from the finger piece G³, so as to expose the latter for a full actuation, but the finger piece can also be partly depressed by inserting the nail of the finger or thumb into the slit L, or into the notch I, seen in 30 these figures while the guard is in the closed or guarding position seen in Fig. 13, and a partial discharge of ink obtained from the reservoir without moving the guard or its controlling sleeve at all, and which is desirable when a new supply of ink for the pen point from the reservoir is required.

The rotation of the sleeve is limited by either the guard or the opposite edge K², of the former impinging against the side of 45 the finger piece as shown in Fig. 2 where the guard is in contact with the finger piece, and Fig. 4, where the opposite edge of the sleeve touches it, thereby rendering as unnecessary the use of any independent means 50 such as a limiting slot and pin arrangement in the barrel and sleeve. This feature can be provided if the sleeve is made of very thin or elastic material, however, and in Fig. 7, two short grooves M, M', in the barrel are 55 shown in which corresponding projections from the bottom of the guard (not shown) can be made to play and thus limit the movement of the sleeve, and thereby guard against any possible opening out of the 60 sleeve by undue strain against the edge of the sleeve while in the position shown in Fig. 4.

The friction of the sleeve upon the barrel is found to be sufficient to hold the guard 65 against the finger piece firmly enough to

guard against accidental movement of the former from the latter, while being free enough to allow of its being drawn away when required by the grip of the thumb and finger upon the outside of the sleeve which is 70 knurled or milled for the purpose, or the guard can also be moved to and from the finger piece by pressing the thumb or finger upon the top of the guard and also pressing it at the same time toward or away from the 75 finger piece. This applies to the movement of the sleeve whether it be moved rotatably as shown in Fig. 4, or slidably as indicated by the dotted lines in Figs. 11 and 13.

In case an additional grip of the sleeve 80 upon the barrel is desired when the shield is in the closed position against the finger piece, this result can be attained by making the sleeve slightly eccentric at some point in its body and the barrel correspondingly cut 85 away so as to cause the compressed part of the sleeve to spring down into the cut away portion of the barrel when the parts come together, and thus make additional resistance to be overcome in moving the guard 90 away from the finger piece. Fig. 14, shows such a construction and in which, the cut away portion of the barrel is indicated at N, that is adjacent to the slot in the barrel and alongside of the finger piece, and in 95 which depression the bottom of the guard and contiguous under surface of the sleeve indicated at O, springs down when the guard is placed alongside of the finger piece as indicated by the dotted lines. By making 100 the groove P, in the barrel as seen in Figs. 11 and 13, slightly larger in diameter at the edge P', than its general diameter is, a similar binding effect can be obtained in that form of the invention, to get additional 105 resistance against accidental movement of the guard away from the finger piece.

The guard moving sleeve can be made with a broad slit as seen in Fig. 7, where it extends across the full width of the sleeve 110 as seen at Q, or it can be as narrow as possible so long as it is wide enough not to allow the edges of the sleeve to come together, and thus lose its tensional grip upon the barrel as indicated in Fig. 3, where the slit is made 115 wide only to the extent of the width of the finger piece and allow for a sufficient amount of rotation or travel for the guard, as indicated at R in said figure.

From the foregoing description and explanation, the nature of the invention can be understood. The matter of different widths of the sleeve is only one of selection, for economy's sake in manufacturing the device, as is that of different widths of the 125 slit in the sleeve. So also are the different shapes of the finger piece, and the rotatable or slidable features of the sleeve which carries the guard to and from the finger piece matters to be determined as to preference by 130

the question of economy of manufacture of the device, as any of the forms shown will work equally well.

All of the figures are intended to show the application of the essential principle of the invention, which is to provide a guard that is high enough to prevent the finger piece against ordinary accidental depression of the finger piece, and yet allow it to be manipulated when wanted to be so done, and to provide a simple means of moving the guard to and from the finger piece as may be desired, which the sleeve device effects as can be seen. The other principle involved is to allow the finger piece to be partially depressed without moving the guard away from the finger piece, when a small jet of ink is to be forced out to the pen point, and the amount of which can be increased to the maximum if the guard is moved to the proper degree away from the finger piece, and thus give the depression of the latter, the requisite regulation and control. These two principles of operation are shown in all of the figures and are based upon having a guard alongside of the finger piece that can be moved away when necessary from the finger piece but allowing for the depression of the finger piece even when the guard is alongside of it, and the top of the finger piece being accessible for manipulation even with the guard against it as indicated in some of the figures.

In Fig. 7, the extremities H^6 , H^7 , of the guard H , are shown as overlapping endwise the end edges of the finger piece as an additional safeguard against impinging objects striking the finger piece endwise and injuring it.

The projecting flange H^2 , in Figs. 9 and 10, which covers the top of the finger piece while allowing the latter to be operated with the finger nail of a person, can be applied in any modified way to the form of guard shown in Figs. 11, 12 and 13, that is the top of either section of the guard (H^6 or H^4) can have a lateral projecting flange like that of the guard H^1 , shown at H^2 , so as to cover the top of the finger piece, or the two sections can be united above the top of the finger piece making the guard integral if desired as shown in Figs. 16 and 17, respectively.

The notch I, in these designs, permits of the depression of the finger piece to any needed degree according to its depth without requiring the movement of the guard away from the finger piece, and this feature can be applied to the guard whether it is in two sections as shown in Figs. 12 and 13, or in one piece or with the projecting flange or cover over the top of the finger piece, as referred to in the preceding paragraph. By placing one's finger nail upon the top of the finger piece thereby securing

a hold upon the latter, it can be depressed partially or fully as may be desired, without moving the guard at all away from the finger piece, and this applies to all of the forms shown and described. This method gives in a single manipulation the ejection of the ink, or the filling of the reservoir, as may be desired, while securing the protection against the accidental depression of the finger piece, all the time.

In the unlocking of the finger piece in a pen having locking rings or other locking mechanisms, and the locking again operation (after the manipulation of the finger piece) there are two manipulations involved in addition to the finger piece manipulation, or three altogether, while by the foregoing described manipulation of this device only a single actuation of the article is required, thus making it so far as is known, the simplest and quickest acting fountain pen in this respect, of any having a protecting member against accidental depression of the finger piece. It is a guard that fully allows for the intentional depression of the finger piece, and without its movement being necessary to do this, while serving to prevent accidental depression of the finger piece, at any time while in its normal position. It as a consequence, differs from all finger piece locking rings, mechanisms or other finger piece binders, and also from other guards or devices that do not allow for the depression of the finger piece while in their normal covering or guarding relation therewith. The sleeve connection serves as a means of connecting the guard to the barrel of the holder, as well as to give it a movable connection therewith, but movement of the guard is not a necessary feature, but desirable as a convenient incidental feature.

From the foregoing description, the operation of the device can be understood without further explanation, as otherwise this pen is put together, the reservoir filled or the ink discharged therefrom by the manipulation of the presser bar mechanism, as with other pens of this general construction and which are now largely in use and well understood.

It can thus be seen that I provide a simple and inexpensive device for the control and regulation of the ink supply in a fountain pen of this class, and that it meets all the requirements of such a device.

Having thus described my invention, what I claim, and desire to secure by Letters Patent, is:—

1. In a fountain pen, the combination of a handle, an ink reservoir, a presser mechanism, and a guard projecting radially outwardly from the handle alongside of the presser mechanism.

2. In a fountain pen, the combination of

- a barrel handle having an opening in its side wall, an ink reservoir within the handle, a reservoir compression mechanism within the handle having a finger piece extending through said opening and beyond the outside of the handle, and a guard movably connected with the handle projecting outwardly therefrom alongside of the finger piece.
- 5 3. In a fountain pen, the combination of a barrel handle, an ink reservoir, a reservoir compression mechanism having a finger piece, a finger piece protecting guard, and a sleeve connected to the base of the guard 10 and frictionally and movably fitted to the handle.
4. In a fountain pen, the combination of a barrel handle having an opening in its side wall, an ink reservoir within the handle, a reservoir compression mechanism within the handle having a finger piece extending outside of the handle through the opening therein, and a finger piece protecting guard 15 20 25
- 20 25 30 35 40

secured to the handle by means of a sleeve movably fitted around the handle and the guard projecting radially outwardly from the handle and alongside of the finger piece.

5. In a fountain pen, the combination of a barrel handle having an opening in its side wall, an ink reservoir within the handle, a reservoir compression mechanism within the handle having a finger piece extending outside the handle through the opening therein, and a finger piece guard having a laterally projecting flange at its outer edge adapted to cover the top of the finger piece and being connected at its inner edge to a sleeve movably fitted over the handle.

Signed at New York, in the county of New York and State of New York, this 23rd day of April, A. D. 1910.
